UNITED STATES PATENT OFFICE.

D. M. CHURCH AND C. H. ELLSWORTH, OF BIRMINGHAM, CONNECTICUT.

BOSOM-EXPANDER.

Specification of Letters Patent No. 28,155, dated May 8, 1860.

To all whom it may concern:

Be it known that we, D. M. CHURCH and C. H. ELLSWORTH, both of Birmingham, in the county of New Haven and State of Connecticut, have invented a new and useful Bosom-Expander; and we do hereby declare that the following is a full, clear, and exact description thereof, reference being had to the accompanying drawings, forming a part 5 of this specification, in which—

Figure 1, represents a perspective view of the expander, showing the form and construction of the same. Fig. 2, represents a sectional view of the same when applied to 10 a person.

Similar letters of reference indicate corresponding parts in both figures.

The object of this invention is to give a full and graceful swell to the chests or bosoms of persons whose chests are naturally flat, so that the shirt and vest may have a handsome and neat fit. It will be found specially useful for soldiers, who, at present use cotton, &c., for expanding their bosoms 20 artificially, which is at certain seasons very warm and uncomfortable.

Our invention consists in a peculiar arrangement of bows of cane, whalebone, metal or other suitable flexible strips united 30 together so as to form a convex, heart-shaped frame covered with any suitable material so as to possess elasticity and flexibility, and provided with suitable hooks and loops for attaching the same to the body, 35 all arranged, combined, and serving the purpose hereinafter described and represented.

To enable those skilled in the art to fully understand our invention we will proceed to 40 describe its construction and use.

In the drawings A is a reed, whalebone or other suitable material covered and bent in the shape of a heart, with the two ends fastened together at the bottom. This 45 frame A is shown in Fig. 1, in red lines. To this frame are suitably attached the ends of strips B and C. These strips cross each other and are connected together at their points of intersection by metal clasps a, and 50 any suitable number may be employed according to the stiffness required to be given.

The frame A is covered with silk, cotton, or other material and if necessary for warmth, a double thickness of material may be secured to the frame to form the back 55 and thickly wadded, but for warm weather a single thickness will be found sufficient. This back serves to keep the frame and bows in shape.

b, b, are hooks projecting from the frame 60 A over which, each side of the shirt bosom is hooked and c is a hook sewed to the bottom of the expander, for keeping the bosom from working up when the expander is on.

d is a loop for keeping the expander in 65 place when applied to the body.

The manner of applying this expander to the body, is to place it between the shirt bosom, and adjust it to a suitable position, and then stretch the bosom so that it will 70 lay smoothly, and attach each side to hooks b, b and the bottom part of the bosom to hook c. The loop d is then attached to the under clothing in such a way that the expander will not be liable to work out of 75 place. The vest is then buttoned up and the bosom will have a gentle swell or curve, from the neck to the waist, giving the appearance of a naturally formed chest or bosom.

In summer such a device will be found 80 very convenient and comfortable for keeping the clothing off from the body and allowing a free circulation of air to the chest. It will be useful to persons who perspire 85 very freely, for keeping the shirt dry and unsoiled. It can be readily applied or removed, and can be made and sold for a comparative trifle.

Having thus described our invention what 90 we claim and desire to secure by Letters Patent as an improved article of manufacture is—

A bosom expander composed of strips A, B, C, hooks b, b, c, loops d, and otherwise 95 made as herein shown and described.

D. M. CHURCH.
C. H. ELLSWORTH.
